UNITED STATES PATENT OFFICE.

FRIEDRICH ARTHUR MAXIMILIAN SCHIECHEL, OF FRANKFORT-ON-THE-MAIN, GERMANY, ASSIGNOR TO THE FIRM OF METALLURGISCHE GESELLSCHAFT, A. G., OF FRANKFORT-ON-THE-MAIN, GERMANY.

MAGNETIC SEPARATOR.

SPECIFICATION forming part of Letters Patent No. 687,579, dated November 26, 1901.

Application filed April 26, 1898. Serial No. 679,030. (No model.)

To all whom it may concern:

Be it known that I, FRIEDRICH ARTHUR MAXIMILIAN SCHIECHEL, mining engineer, residing at Frankfort-on-the-Main, Germany, have invented new and useful Improvements in Magnetic Separators, of which the following is a specification.

This invention has for its object mainly the treatment of weakly-magnetic bodies according to the process as described in the patents to J. P. Wetherill, Nos. 555,792 and 555,793, dated March 3, 1896; and it consists in improvements of such nature which serve to facilitate the treatment of substances which could be separated with the old apparatus and for enabling such substances to be separated of which the magnetism is too weak to admit of the former apparatus being utilized for separating the same. Thus, for example, it was not possible with the old apparatus to utilize for the purpose of separation the very weak magnetism of monazite, zinc-blende, copper pyrites, and other substances whose paramagnetism can be ascertained by the instruments of Faraday, although larger and more effective iron masses were employed as the cores of the magnets. The operation of this machine is such that eventually even an influence can be had upon diamagnetic bodies which would tend to assist the separating of the same from the paramagnetic bodies.

In order to understand the mode of operation of the machine, reference is made to the well-known law that paramagnetic bodies have a tendency in a magnetic field to move from a point of weak concentration of the magnetic lines of force to the point of the highest concentration of these lines of force and that diamagnetic bodies have a tendency to move away from the point of the field where there is the highest concentration. In the magnets of the machines described the place of the highest concentration of the lines of force is a straight plane which connects the two edges of the pole-pieces.

The new apparatus combines the following properties: The edges of the pole-pieces need only be arranged so far apart as is necessary to allow of the passage of the magnetic par-

ticles between them, so that by close juxtaposition a very highly concentrated magnetic field is produced. All raising of the magnetic particles—that is to say, overcoming the force of gravity—is rendered unnecessary. The magnetic particles move along the place of greatest concentration and are acted upon during the whole of this period.

The accompanying drawings illustrate a form of construction of the new machine.

Figure 1 is a side elevation, partly in section. Fig. 2 is a front elevation, and Fig. 3 is a side elevation, of the front edge of the pole-piece on a larger scale. Fig. 4 is an elevation of Fig. 3.

Of the two magnets A and B, which are of a wedge-shaped form, the lower magnet B has the edge of its pole-piece directed with a steep upward inclination, while the pole-piece of the upper magnet A is situated almost horizontal. The two edges of the pole-pieces are adjusted relatively to each other in such a manner that the edge of the magnet B is situated below and slightly to one side of the vertical plane of the edge of the magnet A. (See Fig. 1.) On the edge of the magnet B there is mounted an adjustable thin separating-plate G. The band D, which runs around the front face of the upper magnet A, brings the previously suitably comminuted material, which is supplied by the hopper E and the roller F in a uniform thin layer, as far as the edge of the pole-piece of this magnet, whence it is delivered, describing a parabolic path or trajectory, due to the combined influences of the attraction of gravity and of the onward impulse produced by the motion of the conveyor-band. The separating-plate G is adjusted in such a manner that if the electromagnets are not energized at all the materials brought by the band D will fall exactly and just outside of this plate and will drop down on the right-hand side, Fig. 1, of the lower magnet. In this movement the material passes along and in immediate proximity to the plane of the highest concentration of the lines of force and over its whole extent. If this field be produced by energizing the electromagnets, the weak paramagnetic particles

contained in the material charged into the machine will move out of the general parabolic path of the comminuted material and into the field of the highest concentration of the lines of force and will be caused by this impulse to describe a steeper parabolic path than the non-magnetic constituents. They cannot therefore fall outside of the separating-plate G, but are compelled to fall down on the inner side of the same, (in Fig. 1 to the left of the magnet pole-piece B,) and through and between the two edges of the pole-pieces. It is of course obvious that the speed of the conveyer-band must be proportioned to the power of the magnets, so that the material shall not be delivered at such a rate or momentum as to overcome the influence of the magnets.

Without wishing to restrict the use of the machine to any particular paramagnetic bodies it may be stated that with the aid of this machine the following may be separated, as examples: monazite from quartz, zinc-blende from galena, and copper pyrites from calcareous spar, in which mixtures monazite, zinc-blende, and copper pyrites are the extremely weak paramagnetic substances, while quartz, galena, and calcareous spar are non-magnetic. If now there are in the mixture charged into the machine in addition to very weak paramagnetic and non-magnetic bodies also very strongly diamagnetic bodies, the presence of the latter will not interfere in any way with the separating operation, but rather facilitate it, for in moving along over the plane of highest concentration of the magnetic lines of force the diamagnetic bodies are repelled from the same instead of being drawn downward in the field, and therefore under the influence of the impulse given by the delivery-belt D describe a still flatter parabolic path than either the paramagnetic or non-magnetic constituents, and they therefore pass still more readily over the separating-plate than any of the other constituents of the mass. This action would take place, for example, in the separation of the mixture of zinc-blende, quartz, and native bismuth or of zinc-blende and native bismuth alone. If in the mixture charged into the machine there are any more strongly paramagnetic substances—such as spathic iron ore, hematite—then it may easily be the case that these more susceptible substances may adhere to the edges of the pole-piece of the new machine. The removal of the same is effected at the upper magnet A without further difficulty by the conveyer-band D, while the lower magnet must in this case also be provided with a special stripping-band H, which runs in a similar manner (like the charging-band D around the upper pole-piece edge) around the lower pole-piece edge, as indicated in the dotted lines in Fig. 1. For this purpose the separating-plate G is provided with a recess h, through which the band H passes. The separating-plate may be omitted, if desired, if the pole-piece edge is made

sufficiently sharp and is adjusted with sufficient accuracy.

Although I show the magnets herein as practically in horizontal and vertical planes, it is to be understood that the invention is not limited to this particular arrangement or to any particular angle of inclination of the magnets with respect to each other.

Now what I claim, and desire to secure by Letters Patent, is the following:

1. In a magnetic separator, the combination of a magnet having a pole-piece arranged edge-wise in a substantially vertical plane and means for projecting the material to be treated in a generally horizontal path or trajectory across the plane of said pole-piece, whereby the influence of the magnet shortens the trajectory of the paramagnetic particles and causes them to fall on the near side of said magnet while the remaining constituents of the mass are carried on and fall on the opposite side.

2. In a magnetic separator, the combination of a magnet having a pole-piece arranged edge-wise in a substantially vertical plane, and means for normally projecting the material to be treated from a point on one side of the vertical plane of the pole-piece in a generally horizontal path or trajectory across said plane to the opposite side, whereby the influence of the magnet shortens the trajectory of the paramagnetic particles causing them to fall on the near side of said magnet, and lengthens or flattens the trajectory of the diamagnetic particles causing them to fall farther beyond the magnet than the projecting means would normally deliver them.

3. In a magnetic separator, the combination of a pair of magnets having tapered pole-pieces, said pieces being inclined at an angle to each other, and one being located in a lower plane than the other, whereby the material that passes over the edge of the pole-piece of the upper magnet is given a path or trajectory transverse to the plane of the pole-piece of the lower magnet.

4. In a magnetic separator, the combination of a pair of magnets having tapered pole-pieces, said pieces being inclined at an angle to each other, and one being located in a lower plane than and to one side of the other, and means for delivering the material to be separated over the edge of the pole-piece of the upper magnet in a path or trajectory transverse to the plane of the pole-piece of the lower magnet.

5. In a magnetic separator, the combination of a pair of magnets having tapered pole-pieces, one of said magnets being arranged in a substantially horizontal plane, and the other being arranged edge-wise thereto in a substantially vertical plane below the plane of the other, whereby the material that passes over the edge of the pole-piece of the upper magnet is given a path or trajectory transverse to the plane of the pole-piece of the lower

magnet so that the magnetic particles may fall on the opposite side of the lower magnet from the remaining constituents of the mass.

6. In a magnetic separator, the combination 5 of a pair of magnets having tapered pole-pieces, said pieces being inclined at an angle toward each other, and one being located in a lower plane than and to one side of the other, and an endless carrier traveling around 10 the upper magnet to deliver the material to be separated over and beyond the edge of the pole-piece of said magnet in a path or trajectory transverse to the plane of the pole-piece of the lower magnet.

15 7. In a magnetic separator, the combination of a pair of magnets having tapered pole-pieces, said pieces being inclined at an angle toward each other, and one being located in a lower plane than and to one side of the other, 20 and an endless carrier traveling around the upper magnet for delivering the material to be separated over and projecting it beyond the edge of said magnet, the power of the lower magnet being proportioned to the speed 25 of said carrier so as to overcome the momentum of the paramagnetic particles and prevent them from being carried across the plane of the edge of the lower magnet.

8. In a magnetic separator, the combination 30 of a pair of magnets having tapered pole-pieces, one of said magnets being positioned substantially horizontally, and the other arranged edgewise in a substantially vertical plane below and to one side of the first-mentioned magnet with an intervening space between the edges of the pole-pieces, an endless carrier traveling around the pole-piece of the horizontal magnet and adapted to deliver the material to be treated over and beyond the 35 40 edge of the pole-piece of the vertical magnet, and means for adjusting the width of the

space intervening between the edges of the pole-pieces.

9. In a magnetic separator, the combination of a magnet set edgewise in a substantially 45 vertical position, and having a tapered pole-piece, a plate projecting from the edge of the pole-piece and adjustable so as to vary its inclination relative to the magnet, and means for delivering the material to be separated in 50 a path or trajectory transverse to the plane of the pole-piece of said magnet.

10. In a magnetic separator, the combination of a pair of magnets, one being arranged in a substantially horizontal position, and the 55 other being arranged edgewise in a lower plane and in a substantially vertical position with an intervening space between the edges of the pole-pieces of said magnets, the pole-piece of the vertical magnet being tapered 60 and acting as a mechanical separator for the material falling from upper magnet, and means for delivering the material to be separated into the concentrated field between the respective pole-pieces. 65

11. In a magnetic separator, the combination of a magnet set edgewise in a substantially vertical position said magnet having a tapering pole-piece, a plate projecting from the edge of said pole-piece to separate the 70 material falling in the field of the magnet, means to deliver the material to be separated into the field of said magnet, and an endless band traveling around the magnet for stripping said pole-piece. 75

In testimony whereof I have signed my name to this specification in the presence of two subscribing witnesses.

FRIEDRICH ARTHUR MAXIMILIAN SCHIECHEL.
